US0D1111567S

(12) **United States Design Patent** (10) **Patent No.:** **US D1,111,567 S**
(45) **Date of Patent:** **** Feb. 10, 2026**

(54) **SPRING MODULE**

(71) Applicant: **New-Tec Integration (Xiamen) Co., Ltd.**, Xianmen (CN)

(72) Inventor: **Luhao Leng**, Xiamen (CN)

(73) Assignee: **New-Tec Integration (Xiamen) Co., Ltd.**, Xiamen (CN)

(**) Term: **15 Years**

(21) Appl. No.: **29/899,933**

(22) Filed: **Aug. 15, 2023**

(30) **Foreign Application Priority Data**

May 6, 2023 (CN) 202330260764.4

(51) **LOC (15) Cl.** **06-09**

(52) **U.S. Cl.**

USPC **D6/606**; D6/718.31

(58) **Field of Classification Search**

(57) **CLAIM**

The ornamental design for a spring module, as shown and described.

DESCRIPTION

FIG. 1 is a front elevation view of a spring module showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

1 Claim, 7 Drawing Sheets
